UNITED STATES PATENT OFFICE.

HENRY A. WISE WOOD, OF NEW YORK, AND JOHN A. ISBELL, OF MIDDLETOWN, NEW YORK, ASSIGNEES TO WOOD NEWSPAPER MACHINERY CORPORATION, OF NEW YORK, N. Y., A CORPORATION OF VIRGINIA.

LATE-NEWS-PRINTING DEVICE.

1,414,107.

Specification of Letters Patent. Patented Apr. 25, 1922.

Application filed July 29, 1915, Serial No. 42,492. Renewed October 5, 1921. Serial No. 505,572.

To all whom it may concern:

Be it known that we, HENRY A. WISE Wood and JOHN A. ISBELL, citizens of the United States, said Wood residing at the 5 city, county, and State of New York, said ISBELL residing at Middletown, in the county of Orange and State of New York, have invented a new and useful Late-News-Printing Device, of which the following is a specifica- 10

This invention relates to a fudge or device for adding or inserting small pieces of news in a newspaper after the plates have been cast. As is well known, these devices 15 are used in printing afternoon papers and ordinarily a fudge is provided with an individual inking mechanism of its own.

The principal objects of this invention are to so combine the fudge with the rest of the 20 press that no separate inking mechanism will be required, thus reducing the expense to that extent, and furthermore to provide an arrangement whereby when the inking mechanism is moved away from the plate cylinder, it is also moved away from the fudge. Thus it leaves a space between each of these 25 cylinders and the inking mechanism so that an operative can enter and make any desired change.

30 Reference is to be had to the accompanying drawings in which,

Fig. 1 is a side view of a portion of a press provided with a preferred embodiment of this invention; and

35 Fig. 2 is an end elevation of the same, not showing the inking mechanism but looking at the printing mechanism from the line 2-2 of Fig. 1 in the direction of the arrows.

40 The invention is shown as applied to a press designed by us, but not constituting a part of this invention and consequently not shown in full.

Referring to the drawings, it will be seen 45 that the apparatus is shown as mounted on the usual press side frames 7. The impression cylinder 8 and plate cylinder 9 of the printing couple of a perfecting press are shown in their usual positions. Fastened 50 to one end of the plate cylinder shaft is a bevel gear 10. By means of a pinion 11 secured to a vertical shaft 12 journalled on a bracket 13 and gears 14 and 15, this gear 10 drives the late news impression cyl-

inder 16, on the shaft of which the miter gear 15 is fixed. This cylinder 16 preferably is of one-half the diameter of the impression cylinder 8, or equal to one paper length in circumference.

The fudge impression cylinder 16 carries 60 on each end a pinion 17. These pinions mesh with gears 18 on fudge cylinder shafts 19 and 20 located in alignment across the press. The fudge impression cylinder 16 is supported in suitable bearings 21 on the 65 press frames 7. The fudge cylinder shaft 19 is supported on a bearing 22 in the press frame and a bearing bracket 23 fastened to a brace 24 extending between the press frames. The shaft 20 is similarly supported 70 on bearings 25 and 26. These two shafts 19 and 20 carry the usual fudge cylinders 27 having fudge boxes 28. The fudge boxes are filled with linotype slugs, one or two columns wide, and fastened on the fudge 75 cylinders by means of lock nuts 29. It will be understood that these fudge cylinders can be moved along their respective shafts so as to print in any column of the paper, or two adjacent ones.

The inking apparatus shown in these figures consists of an ink fountain 30 having a roll 31 as usual, and a pick-up roller 32. The fudge cylinder form roller 33 which applies the ink directly to the two fudge cylinders 85 extends across the frame and is in contact with the pick-up roller 32. It is mounted in adjustable bearings on the ink carriage frame 38. Its composition surface can be cut away if desired, as is well understood, 80 so as to transfer ink only to the pages covered by the fudge cylinders.

The inking mechanism also comprises an ink roller 34 conveying ink from the pick-up roller 32 to the ink cylinder 35 and other 95 ink rollers 36 and form rollers 37. This whole inking mechanism, including the roller 33, is supported on carriage frames 38 and adapted to slide in and out of inking contact with the plate cylinder 9 and the fudge 100 cylinders. It slides on horizontal press frames 39 connected with the press side frames 7. The position of the press when inking is shown in full lines in Fig. 1 and the position when drawn back in dotted 105 lines. When drawn back the plate cylinder and the fudge cylinder are both exposed and a space is left between them and the

inking mechanism so that an operator can get in between them to perform any necessary changes.

The operation of the device is as follows:—

- 5 The ink carriage 38 is first moved back to the dotted line position in Fig. 1, thus providing room for the operator to enter and insert the fudge boxes in the fudge cylinders. The cylinders are then shifted to the
- 10 desired spaces. The fudge cylinder shafts can be adjusted by means of the ordinary adjustable gears 18 thereon so as to turn the cylinder to register it with the previously printed page. The carriage is then moved
- 15 to its working position, as shown in full lines, and locked to the main press frames and the fudge form roller 33 adjusted to transfer ink properly from the pick-up roller 32 to the fudge cylinder.
- 20 Although we have illustrated and described only one from of the invention, we are aware of the fact that many modifications can be made therein by any person skilled in the art without departing from the
- 25 scope of the invention as expressed in the claims.

Therefore, we do not wish to be limited to the details of construction herein shown and described or to the particular combinations 30 of parts set forth, but what we do claim is:—

- 35 1. The combination of a printing couple, a fudge cylinder and its impression cylinder with an inking mechanism comprising a fountain roll, a pick-up roll, form rollers, ink distributing members between the pick-up roll and form rollers, and a second form roller in contact with the pick-up roll in position to supply ink to the printing couple
- 40 and fudge cylinder simultaneously.

2. The combination of a printing couple, a fudge cylinder and its independent impression cylinder, with an inking mechanism having separate means for supplying ink to both the printing couple and fudge cylinder, 45 said inking mechanism being bodily movable directly away from the fudge cylinder and the printing couple to afford a space between them.

3. The combination with a printing couple 50 of a fudge cylinder adapted to print on the same web with an inking mechanism comprising a fountain roll, a pick-up roll, an ink cylinder, ink rollers around the ink cylinder, a form roller, and a second form roller 55 in contact with the pick-up roll and in position to supply ink to the fudge cylinder, said inking mechanism being bodily movable directly away from the fudge cylinder to afford a space between them.

4. In a fudge device, the combination with two independent fudge cylinders, of an ink fountain roll, a pick-up roller, and an independently and laterally adjustable form roller for transferring ink from the pick-up 65 roller to both fudge cylinders.

5. In a late news printing device, the combination with a press and its printing couples, of two shafts located in alignment across the press and each adapted to support 70 a fudge cylinder, and means carried by the press for conveying ink to the fudge cylinder on each shaft.

In testimony whereof we have hereunto set our hands, in the presence of a subscribing witness.

HENRY A. WISE WOOD.
JOHN A. ISBELL.
